CIRCUIT INTERRUPTER CONTACT PRESSURE INCREASING DEVICE

Andrew W. Edwards, Pittsburgh, Pa., assignor to
Westinghouse Electric Corporation, East Pittsburgh, Pa., a corporation of Pennsylvania

Application October 11, 1947, Serial No. 779,277

14 Claims. (Cl. 200—87)

1

This invention relates generally to electric circuit interrupters and more particularly to such interrupters having electro-responsive means for opening the interrupter contacts against a contact-closing bias.

In circuit interrupters of this type it is generally desirable to keep the contact-closing bias as low as possible in order to limit the size of the electrical contact opening device. One example of such a device is an automatic reclosing circuit breaker having a series coil to separate the breaker contacts against a closing bias. Inasmuch as the energy required to open the contacts of such a circuit breaker is directly proportional to the contact pressure, the high contact pressures required to prevent opening of the contacts due to the magnetic forces encountered on short circuit conditions, require an undesirably large size of operating coil.

One object of this invention, therefore, is to provide in a circuit interrupter, means for automatically increasing the contact pressure in response to increases in current carried by the contacts, while at the same time not imposing any appreciable increase in the amount of force required to separate the contacts.

Another object of this invention is to provide in a circuit interrupter, novel means providing sufficient pressure on the contacts to prevent them from opening due to the magnetic forces present under short circuit conditions while at the same time permitting separation of said contacts by a much lesser force.

Another object of this invention is to provide in a circuit interrupter having current responsive magnetic means for separating the interrupter contacts, novel means causing the magnetic means to increase contact pressure on overloads and to remove such increased pressure at least when said magnetic means effects actual contact separation.

These and other objects of this invention will become more apparent upon consideration of the following detailed description of the preferred embodiments thereof, when taken in connection with the attached drawing, in which:

Figure 1 is a substantially central vertical section view of a circuit breaker embodying this invention; and

Fig. 2 is also a substantially central vertical section view of a part of a circuit breaker like that shown in Fig. 1, but illustrating another embodiment of the invention.

This invention is illustrated on the drawing as being embodied in one form of automatic reclos-

2

ing circuit breaker, with the particular breaker herein illustrated being more particularly described and claimed in the copending applications of J. M. Wallace et al., Serial No. 719,524, filed December 31, 1946, on Circuit Interrupters; J. M. Wallace et al., Serial No. 719,572, filed December 21, 1946, on Circuit Interrupters; and J. M. Wallace et al., Serial No. 718,942, filed December 28, 1946, on Circuit Interrupters, and issued November 20, 1951 as Patent No. 2,575,738; all of which are assigned to the same assignee as this invention. This circuit breaker is mounted in a metal tank 2 having a closed bottom wall and an open top and adapted to be filled with a liquid up to the level L, preferably an arc extinguishing liquid such as oil or the like. Preferably, the tank is lined at least over the bottom wall and up to a point adjacent the open top of the container with a liner 3 of insulating material such as fiber, or the like. The upper end of tank 2 is provided with an outwardly extending flange 4 on which the flange 8 of a cover casting 6 is adapted to be seated, preferably, with a gasket 10 interposed therebetween. Flange 8 of cover casting 6 may be provided with an integral lip 12, and the cover may be secured to the tank in any desired manner, such for example as by bolts (not shown) extending through openings in cover flange 8 and secured to suitably formed brackets on the tank.

The breaker contacts, arc extinguishing structure and the contact actuating mechanism are all adapted to be supported in tank 2 from cover casting 6 by means of a pair of integral supporting lugs 16 (only one of which is shown) depending from the top wall of the cover casting and adapted to engage spacer sleeves 18 of insulating material suitably secured to supporting lugs 16 and to a supporting casting 20. A supporting plate 22 may be supported from casting 20, so that a solenoid coil 24 may be mounted between casting 20 and supporting plate 22, with the central opening in the coil aligned with openings provided in casting 20 and plate 22. Supporting casting 20 and supporting plate 22, together with the bolts (not shown) securing them together are of a magnetic material, such as iron or the like, to complete a magnetic circuit of low reluctance outside of solenoid coil 24, which terminates at opposite ends of the central opening through the coil in which the working air gap of the coil is located.

Spaced stationary contacts 26 of the breaker are each supported from plate 22 by a support 55 28 of insulating material, such as fiber, formed

of inverted U-shape, with the stationary contacts being mounted in openings provided in the base portions 30 of each support 28, and with the upper ends of each support 28 having laterally extending flanges 32 by means of which each support is secured to supporting plate 22. As illustrated, each contact 26 is formed as the head of a bolt 38 to which a conductor may be secured, as by the nuts 34.

Stationary contacts 26 are adapted to be closed by engagement therewith of a bridging contact 36 having contact tips 38 at opposite ends thereof for engagement with the stationary contacts, respectively. Bridging contact 36 is supported substantially centrally thereof on a slideable contact actuating rod 44 by a pivot pin 40 for limited pivotal movement about a transverse axis. Contact rod 44 being mounted for longitudinal sliding movement through coil 24 and aligned openings in plate 22 and casting 20, it will be observed that bridging contact 36 is free to adjust itself to the stationary contacts by restricted pivotal movement about its pivotal mounting 40. Contact rod 44 should be of an insulating material such as fiber or a molded insulating material.

The supports 28 for stationary contacts 26 form arc extinguishing means for the arcs drawn between the ends of the bridging contacts 36 and stationary contact 26, respectively, when the bridging contact is moved upwardly to open the circuit.

The upper end of contact actuating rod 44 has connecting links 46 pivoted thereon as by a pivot pin 48, with the upper ends of these connecting links mounted on a common pivot pin 50 for a pair of toggle levers 52 and 54. Toggle levers 52 and 54 are both formed of sheet material, with lever 54 being bent to substantially channel form with outwardly extending flanges 56 adapted to be received at the free ends thereof in recesses 58 provided in the spaced downwardly depending fingers of an angled supporting bracket 60 which, in turn, is secured as by a screw 64 to a lug 62 integral with the cover casting. A coil tension spring 68 has one end hooked into an opening provided in toggle lever 52, and has the opposite end thereof hooked over an integral spring support on the cover casting. Toggle lever 52 has an integral hook portion 55 passing through an opening in lever 54 to limit separation of the levers.

It will be observed that in the closed circuit position of the breaker illustrated on the drawing, the line of action of toggle spring 68 is below the pivot supporting recesses 58 for toggle lever 54, and accordingly, the toggle spring acts to bias bridging contact 36 into engagement with stationary contacts 26 of the breaker, under a predetermined pressure. However, as soon as contact operating rod 44 moves upwardly to separate the bridging contact from the fixed contacts of the breaker, toggle lever 54 will pivot about recesses 58 and the line of action of toggle spring 68 will thus be caused to approach that pivot point so that in response to a very small contact separation the line of action of toggle spring 68 will pass through pivot recesses 58 which is the on-center position of the resilient toggle arrangement comprising toggle levers 52 and 54 and toggle spring 68. As a practical matter, the opening movement of the contacts necessary to move toggle levers 52 and 54 to the on-center position mentioned above may be made very small, in one actual device being on the order of one-quarter of an inch. When toggle levers

52 and 54 reach their on-center position referred to above, further relative movement of the two toggle levers in the same direction is prevented because the upper edge of toggle lever 52 engages the base of the central channel formation of toggle lever 54. Moreover, since the point at which toggle spring 68 is hooked into lever 52 then substantially coincides with recesses 58 in which toggle lever 54 pivots during contact opening movement, it will be apparent that the remainder and major part of contact opening movement will occur substantially uninfluenced by toggle spring 68.

Substantially the reverse of the above operation occurs when contact operating rod 44 moves downwardly to close the circuit from the full open contact position, because during the first and major part of contact closing movement, levers 52 and 54 will be in engagement so that such movement will be uninfluenced by toggle spring 68. However, as soon as pivot 50 passes below a line drawn from the remote end of toggle spring 68 through pivot recesses 58 for link 54, toggle spring 68 will then be effective to move the toggle levers toward the full line position shown in Fig. 1, and the force exerted by toggle spring 68 thus tending to close the contacts will continue to increase as toggle levers 52 and 54 move further away from their on-center positions.

30 Solenoid coil 24 previously mentioned is adapted to be energized under certain conditions for automatically opening the circuit breaker contacts. The central opening through coil 24 preferably is provided with a cylindrical sleeve 74 in which a solenoid core 76 is adapted to be slidably mounted in a piston-like manner. Core 76 is in the form of a cylindrical sleeve having opposed slots 78 in the upper portions thereof adapted in the normal closed circuit position of the device illustrated in Fig. 1 to extend partly above and partly below supporting plate 22, by engagement of an exterior shoulder 83 adjacent the upper end of the core with a sleeve 80 which has an external rib 85 held between the sleeve 74 for the coil and supporting plate 22. The lower end of core 76 is provided with opposed openings 81, for a purpose to be hereinafter described.

50 A contact actuating sleeve 82 is telescoped over contact actuating rod 44 and its lower end is received in core 76 preferably being threadably mounted therein. A coil compression spring 86 is provided within actuating sleeve 82 on contact actuating rod 44 and it is adapted to react between core 76 and a pin 88 extending transversely through actuating rod 44.

55 The circuit through the circuit breaker thus far described may now be traced from the points where it enters tank 2 through one of a pair of terminal bushings 90 (only one being shown), with each bushing being secured to cover casting 6 as by bolts 94, and each being provided with a conductor element which extends through the bushing and emerges from a reduced extension 96 of the bushing seated in an opening provided in the top wall of cover casting 6. The circuit proceeds by conductor 98 directly to one fixed contact 26 of the breaker. When the contacts 70 are in engagement, the circuit then proceeds through bridging contact 36 to the other fixed contact 26, and then by way of a conductor 100 to one terminal of solenoid coil 24. The other terminal of coil 24 is adapted to be connected by 75 a conductor 102 to the conducting means in the

other terminal bushing 90. It will be apparent that solenoid coil 24 is connected in series in the circuit through the circuit breaker so as to be energized at all times an amount dependent upon the value of the load current flowing in the circuit.

For any given rating of circuit breaker, solenoid coil 24 is designed to become sufficiently energized when the load current in the circuit exceeds its rating as to attract core 76 and move it upwardly within sleeve 74. Assuming the upper end of sleeve 74 to be closed so fluid cannot escape, core 76 will move upwardly relatively rapidly until the bottom of slots 78 reaches sleeve 80, whereupon there is no longer any vent for fluid contained in cylindrical sleeve 74, and it then becomes necessary upon further upward movement of core 76 to displace the liquid in sleeve 74 above the core through the relatively small clearance between the core and sleeves 74 and 82. Accordingly, opening movement of the core will be slowed up by the aforesaid dashpot action an amount determined by the current value of the overload, and, therefore, an inverse time-current characteristic on opening is obtained. Finally, when openings 81 clear the upper edge of sleeve 80, the space within sleeve 74 is freely vented through openings 81 to the bottom of core 76, so that core 76 will no longer be restrained by the dashpot action, and the final opening movement thereof may be relatively rapid. As soon as core 76 commences its upward travel, bridging contact 36 being held engaged by toggle spring 68 does not move, so that spring 86 is compressed until the energy stored in spring 86 is sufficient to overcome the force exerted by toggle spring 68, at which time contact actuating rod 44 will start to move upwardly. As soon as actuating rod 44 moves upwardly, the force exerted by toggle spring 68 begins to decrease and in a very short distance has substantially no value at all, so that the remaining major part of the circuit opening movement of bridging contact 36 occurs extremely rapidly due to expansion of spring 86. Flange 89 is provided on rod 44 to obtain a positive contact separation in the event there is any sticking or welding of the bridging contact to stationary contacts 26, by engagement therewith of a shouldered sleeve 83 mounted in the upper end of actuating sleeve 82. In either case, it is apparent that toggle levers 52 and 54 will be moved to their on-center position in the manner previously described, and bridging contact 36 will be moved by spring 86 to its full open circuit position.

When the breaker contacts have attained their full open circuit position, the parts associated therewith are biased to return by gravity. This closing bias is relatively light and will be opposed by the dashpot action of core 76. Accordingly, the return movement will be relatively slow until pivot point 50 moves below the line of action of toggle spring 68 when toggle levers 52 and 54 are in engagement, whereupon bridging contact 36 will be rapidly moved to effect a snap-action closing of the breaker contacts by toggle spring 68. Moreover, at about this same time the lower ends of slots 78 in core 76 will clear the lower edge of sleeve 80 so as to vent the dashpot comprising sleeve 74 and core 76.

In order to provide for maintaining the breaker contacts separated and to also provide for manual operation, spring means are provided for holding the breaker contacts open in response

to the occurrence of a predetermined number of closely succeeding circuit interrupting operations, which means can be manually actuated. This means comprises a toggle lever 104 having a slot 106 at one end thereof for receiving a pin 108 mounted between spaced supporting arms 110 integral with cover casting 6. The other end of toggle lever 104 is pivoted, as by a pivot pin 112, to the adjacent end of a second toggle lever 114, and this, in turn, is mounted on a pivot pin 116 intermediate its ends on cover casting 6. A slot 120 is provided through the cover casting 6 for receiving the other end of toggle lever 114 which acts as a manual operating handle at the exterior of the circuit breaker casing, being provided with a hook eye 122 in its outer end. A coil compression spring 124 is mounted on toggle lever 104 and reacts between washers mounted on the toggle lever, one of which engages supporting pin 108, and the other of which engages a shoulder located adjacent pivot 112. Normally, toggle levers 104 and 114 are held with pivot 112 below the center-line connecting pins 108 and 116, with the outer end of lever 114 positioned in and beneath an integral hood 126 on cover casting 6, in engagement with an adjustable stop screw 128 mounted in the hood.

In the position of toggle levers 104 and 114 illustrated, they have no effect on operation of the circuit breaker as previously described, being normally inactive in this respect. However, the common pivot pin 112 of toggle levers 104 and 114 is extended at one side toward toggle levers 52 and 54 and in the normal position of the parts extends beneath the adjacent flange 56 of toggle lever 54. Accordingly, if it is desired to manually open the circuit breaker contacts, a hook stick or similar operating member may be inserted in hook eye 122 of toggle lever 114 and pulled downwardly to rotate the toggle lever in a counterclockwise direction about its supporting pivot 116 to move toggle levers 104 and 114 overcenter in an upward direction, and in doing this, the common pivot pin 112 engages the adjacent flange 56 of toggle lever 54 and moves it upwardly in a counterclockwise direction, thus carrying contact actuating rod 44 with it to separate bridging contact 36 from stationary contacts 26. The contacts will be held open by spring 124 which maintains toggle levers 104 and 114 in their upper overcenter position. With the breaker contacts maintained at their open circuit position following the manual circuit opening operation described above, it will be apparent that the outer end of toggle lever 114 projects below hood 126 of cover casting 6 so as to provide a readily visible indication that the breaker contacts are maintained at an open circuit position. It will further be apparent that the breaker contacts may then be closed only by manual operation of toggle lever 114 in the opposite direction, that is, by exerting an upward force on the outer end of the toggle lever to rotate it in a clockwise direction to move it and toggle lever 104 back overcenter to the full line position illustrated on the drawing. This manual operation of toggle lever 114 does not directly close the breaker contacts but merely permits closure of the contacts in the manner previously described, that is, initial closing movement of the contacts being due to the bias of gravity, until bridging contact 36 is closely adjacent stationary contacts 26 when toggle spring 68 is moved below its on-center position and suddenly becomes effective to finally move the contacts into engagement rapidly.

An integrating mechanism for automatically moving toggle levers 104 and 114 upwardly over center and thus preventing reclosure of the circuit breaker only in response to a predetermined number of closely successive circuit interrupting operations, and at the same time for automatically controlling the circuit opening and closing times in a predetermined manner in any sequence of a plurality of closely successive circuit opening operations, is provided comprising a cylindrical tube 130 secured in casting 20, and this tube has a plug 132 threaded into the lower end thereof with the plug having a small central opening controlled by a ball-check valve 134, which permits flow of fluid into the lower end of tube 130 but prevents outflow. An integrating piston 136 is mounted in cylindrical tube 130 and normally rests on the upper end of plug 132, being provided with a reduced extension 138 at the upper end thereof, having a plurality of spaced circular flanges 140 forming rack teeth thereon, and having an elongated extension 142 on the extreme outer end thereof which is positioned below an extension 143 on toggle lever 104. A pawl lever 144 is pivotally mounted at one end as at 146, this end of pawl lever 144 being split with legs located at each side of tube 130 and with pivot 146 supported on spaced supporting flanges 141 integral with casting 20. Pawl lever 144 has a connecting web intermediate its ends, and at the other end thereof the sides of the lever are extended outwardly and laterally as at 148, to normally be in engagement with a washer 150 mounted on sleeve 82 in engagement with an exterior shoulder on this sleeve. Pawl lever 144 is normally biased into engagement with washer 150 by a coil tension spring 152 hooked over the remote edge of the web of the pawl lever at one end and anchored to an ear integral with casting 20 at its other end. Pawl lever 144 is provided with a pawl member 154 pivoted thereon as at 156, and biased by a spring 158 in a counter-clockwise direction to a position wherein a portion of pawl member 154 engages the connecting web of pawl lever 144.

In order to control the opening and closing times of the circuit breaker contacts to provide for different opening and closing times on predetermined circuit opening and closing operations in any sequence of closely successive operations, as on continuing overloads, the dashpot formed by sleeve 74 and solenoid core 76 has a vent 174 at the upper end thereof which is annular in form being provided in casting 20 about actuating sleeve 82. Annular vent 174 communicates with a laterally extending passage 176 also formed in casting 20, so that fluid may escape from the upper end of sleeve 74 through annular vent 174 and passage 176, and then through a pair of opposed openings 178 in tube 130, from whence it may escape through a discharge opening 180, also formed in casting 20. The openings 178 in integrator tube 130 are aligned with passage 176 and discharge opening 180.

With the parts of the circuit breaker at their normal positions illustrated in Fig. 1, it will be apparent that when the circuit breaker operates to open the circuit, the upper end of dashpot sleeve 74 being open through annular vent 174, passage 176, openings 178 and discharge opening 180, solenoid core 76 will be moved very rapidly upwardly since the liquid in dashpot sleeve 74 above the core may be freely vented through the vent passages mentioned above, and consequently the initial circuit opening operation of the breaker

will occur substantially instantaneously. As solenoid core 76 moves upwardly, washer 150 will be carried upwardly with actuating sleeve 82 and thus carry the free end of pawl lever 144 upwardly with it to move pawl member 154 into engagement with the upper one of flanges 140 on integrating piston 136, to thus carry the piston upwardly a predetermined distance throughout opening movement of sleeve 82. Integrating piston 136 is not, however, carried upwardly a distance sufficient to entirely remove reduced portion 138 thereof from between openings 178 in cylinder 130, so that the vent passageway from the upper end of dashpot cylinder 74 will not be blocked off by piston 136. When the breaker recloses following such a first circuit interrupting operation, such reclosure will also occur extremely rapidly because core 76 does not have any dashpot action in its dashpot sleeve 74 due to the upper vent for the sleeve still being open. Accordingly, the first opening and reclosing of the circuit breaker contacts will both occur substantially instantaneously with no time delay interposed due to the dashpot action of core 76 in dashpot sleeve 74. During reclosing of the breaker the first time, integrating piston 136 is left at the position to which it was advanced, since pawl member 154 is free to disengage the circular flanges 140, and if the breaker remains closed, integrator piston 136 will slowly reset to the position shown in Figs. 1 and 2, this resetting movement being relatively slow due to the necessity of displacing liquid drawn into the lower end of cylinder 130 by advancement of piston 136 during the opening operation, past the relatively small clearance between cylinder 130 and piston 136. This means, of course, that if an overload appears on the circuit at a later time, the breaker contacts will then be substantially instantaneously opened and closed in the manner described above.

However, if the breaker immediately reopens after a first opening and reclosing operation, pawl member 154 this time will engage the next lower circular flange 140 on the integrator piston 136 and raise the piston a further amount sufficient to bring the piston between side openings 178 of integrator cylinder 130, so that the integrator piston acts as a valve to close off the vent passage 174 from the upper end of dashpot cylinder 74. Inasmuch as the integrator piston 136 does not close the vent passage until bridging contact 36 is substantially at the end of its circuit opening movement, this second closely successive circuit opening operation will, like the first, occur substantially instantaneously with substantially no delay due to dashpot cylinder 74 and core 76. However, on the succeeding reclosing operation, integrator piston 136 having closed the vent at the top of dashpot cylinder 74, this reclosing operation will be delayed in the manner previously described by the dashpot action of core 76 in cylinder 74. This second reclosing operation will result in leaving piston 136 at the further advanced position described above, from which it eventually will reset in the manner previously described if the breaker remains closed, so that an overload appearing on the circuit at a later time will result in the breaker operating in the manner described above for the first and second closely succeeding circuit opening and closing operation. However, in the event the overload continues after the second closely succeeding circuit opening and closing operations, the breaker will again open, and this time the opening operation will be delayed by the dashpot action of core

76 in dashpot sleeve 74, since integrator piston 136 has not had time to recede from the position to which it was advanced on the second opening operation of this series of closely succeeding circuit opening operations, where it blocks the vent passage from the upper end of dashpot sleeve 74.

The circuit closing operation of the breaker following the third opening will be delayed in the manner previously described, inasmuch as such third opening operation results in further advance of integrator piston 136 where it still blocks the vent passageway from the upper end of dashpot sleeve 74. The breaker may then continue to open and reclose if the overload continues, with each opening and closing being delayed by the dashpot action of core 76 in dashpot sleeve 74 until finally pawl member 154 advances integrator piston 136 an amount sufficient to cause the upper extension 142 thereof to engage the extension 143 of toggle lever 104, and move this lever upwardly over center so that toggle spring 124 will maintain the contacts separated in the manner previously described. It is thus apparent that toggle levers 104 and 114 will be automatically moved upwardly over center to maintain the breaker contacts separated only in response to a predetermined number of closely successive circuit opening and closing operations, usually four such operations; however, in the event a lesser number of closely successive opening and closing operations occurs, the integrating mechanism will reset and the breaker contacts will be automatically held open only when the predetermined number of opening and closing operations occurs in close succession. Obviously, after the breaker contacts have been automatically actuated to a position where they are held open by toggle spring 124, they can be reclosed only by manual operation of toggle lever 114 in the manner previously described.

In the preferred sequence of operations leading to the breaker contacts being maintained in open circuit position mentioned above, that is a sequence of four operations, it will be apparent that with the apparatus described above, the first two opening operations will occur substantially instantaneously and the second two opening operations will be delayed with an inverse time-current characteristic due to the dashpot action of core 76 in dashpot sleeve 74. Moreover, the reclosing times in any such sequence of four closely successive opening and closing operations will comprise a first substantially instantaneous closing operation, with the remaining circuit closing operations being delayed by the dashpot action of core 76 in dashpot sleeve 74.

If desired, a protective gap device 166 of the expulsion type may be provided to prevent operation of the breaker on voltage surges, with the outer tube of the protective device mounted intermediate its ends on an extension 168 of supporting plate 22 at the underside of solenoid coil 24, being secured thereto as by nuts 170 threaded on the tube of the protector device. One terminal 172 of the protective device may be connected with conductor 100 and one side of solenoid coil 24, with the other terminal of the protective device (not shown) connected with the other terminal of coil 24 and conductor 102. This arrester and its particular manner of mounting and connection with this type of apparatus is more particularly disclosed and claimed in the copending application of H. L. Rawlins and J. M. Wallace, Serial No. 694,074 on Overvoltage Protective Devices, filed August 30, 1946, now issued

as Patent No. 2,550,124 on April 24, 1951, and assigned to the same assignee of this invention. As stated above, the purpose of providing a protective device 166 connected in the manner described herein and in the aforesaid copending application is to provide a by-pass for solenoid coil 24 on voltage surges such, for example, as those due to lightning strokes, which are not overloads on the circuit and, consequently, it is not desired that the breaker open on such surges.

With most contact constructions, and the contact structures shown in Fig. 1 are no exception, the magnetic and mechanical forces are such that on high values of current these forces may cause separation of the contacts and hence cause arcing at unauthorized times with the attendant dangers and bad effects thereof. Thus, with the contact structure shown in Fig. 1, on high overload currents, such as short-circuit currents, the flux crowded in the corners defined by the bridging contact 36 and bolts 186 produces a relatively high force tending to move bridging contact 36 upwardly away from fixed contacts 26. Moreover on extremely high currents the temperature of the contacts may get so high as to melt and cause a boiling of the material of the contact faces which creates a mechanical force tending to separate the contacts. In order to prevent this it is necessary that an extremely strong contact pressure spring 68 be provided, and, of course, the stronger spring 68 is made to be, the larger coil 24 must be to overcome that spring.

In accordance with this invention, spring 68 need only be strong enough to exert sufficient contact pressure to prevent opening of bridging contact 36 on currents not substantially higher than normal load currents. Upon the occurrence of overload currents, particularly those of high value, such as short-circuit currents, the pin 88 which also forms the upper reaction point for coil spring 86, is made to be of a magnetic material, such as iron, so that when such high currents pass through coil 24, pin 88 being at the opposite end of the working gap of the coil from core 76, the attraction of pin 88 to the core causes contact rod 44 to be pulled downwardly with a relatively large force augmenting that of contact pressure spring 68. This action causes the contact pressure to be quite large and prevents premature contact opening due to the magnetic forces induced by such high currents at the contacts. This, of course, is of particular importance in an automatic reclosing circuit breaker of the type disclosed herein where certain operations are delayed by the dashpot action of core 76 in dashpot sleeve 74 for purposes of coordinating with other interrupting apparatus in the circuit, such as fuses. Obviously, if the contacts open prematurely, the purpose of providing time delay is destroyed. However, even on the instantaneous opening operations of the breaker, it is highly desirable that the contacts do not separate before they are made to separate by core 76, in order to keep the arcing time at a minimum. As core 76 moves upwardly, it compresses spring 86, as previously described, and works against the magnetic and spring forces holding the contacts closed. As core 76 approaches the lower end of the flange 175 extending from casting 20 into solenoid coil 24, the flux path to pin 88 is shortened so as to effectively magnetically shunt pin 88 out of the magnetic circuit with the result that it ceases to exert any substantial contact pressure. The parts are arranged so that this decrease in contact pressure due to the magnetic

effect of pin 88 occurs at substantially the same instant that the contacts are parted by core 76, either by force stored in spring 86, or by engagement of the upper end of sleeve 83 with collar 89 on the contact rod.

Because it has been found desirable to keep the area of such magnetic material relatively small in order that the flux acting thereon to augment contact pressure may be most effectively shunted out at the time the contacts are actually separated by the solenoid, but a small amount of magnetic material need be provided on contact rod 44 as exemplified by pin 88. Of course it is not necessary that the flux to pin 88 be shunted out at the upper end of movement of core 76, because if the mass of magnetic material on contact rod 44 is kept small, the force due to its flux will be small relative to the force due to the flux to the stationary frame 28 of magnetic material. Pin 88 thus might be positioned on rod 44 below the lower end of the flange on casting 20, although the particular arrangement illustrated is preferred. It is apparent that other forms of magnetic material could be employed however, such, for example, as the collar 182 of magnetic material illustrated in Fig. 2. Collar 182 may be secured to contact rod 44 in any desired manner, such, for example, as by riveting or the like, and acts to augment contact pressure, especially when high currents are present in the circuit, in the same manner as the pin 88 of Fig. 1. Inasmuch as all the remaining parts shown in Fig. 2 are identical with corresponding parts shown in Fig. 1 and the same reference numerals are applied thereto, it is believed that the operation thereof is readily apparent from the above description of operation of the device shown in Fig. 1, and accordingly a complete description thereof for the parts shown in Fig. 2 will not be given in order to avoid repetition.

It is believed apparent that in accordance with this invention there is provided means for augmenting contact pressure when it is needed on heavy overload currents, such as short-circuit currents, with provision that such augmented force is relieved at least by the time the circuit breaker contacts are actually separated. More specifically, the augmented contact pressure is obtained by providing magnetic material associated with the contacts in a magnetically operated switch, which material also acts as a support for one end of the spring which takes up lost motion between the contacts and the magnet core.

Having described preferred embodiments of the invention in accordance with the patent statutes, it is desired that this invention be not limited to these particular constructions inasmuch as it will be apparent, particularly to persons skilled in this art, that many modifications and changes may be made in these particular structures without departing from the broad spirit and scope of this invention. It will thus be readily appreciated that the invention may be employed with other types of circuit breakers, or even with circuit controlling devices other than circuit breakers.

I claim as my invention:

1. A circuit interrupter, comprising, separable contacts which are biased into engagement, contact separating means having a part movable a predetermined amount before causing separation of said contacts, means acting on said contacts and responsive to overload currents in the circuit

to exert additional pressure on said contact, and means cooperating with said additional pressure means and positioned to be operated by said part at a point adjacent but spaced from the end of its aforesaid movement to render said additional pressure means substantially less effective just before said part causes separation of said contacts.

2. A circuit interrupter, comprising, separable contacts which are biased into engagement, contact separating means having a part movable a predetermined amount before causing separation of said contacts, means acting on said contacts for exerting additional pressure on said contacts to prevent opening of said contacts by the magnetic forces due to current overloads, and means cooperating with said additional pressure means and positioned to be operated by said part at a point adjacent but spaced from the end of its aforesaid movement to render said additional pressure means substantially less effective just before said part causes separation of said contacts.

3. A circuit interrupter, comprising, separable contacts which are biased into engagement to automatically close the circuit following a circuit interrupting operation, a solenoid coil connected in series circuit relation with said contacts, a solenoid core biased to a normal position at one end of the working gap of said coil and from which it is moved by attraction of said coil on overload currents a predetermined distance before causing movement of one of said contacts away from the other to open the circuit, and means of magnetic material secured to said one contact and being positioned in said working gap at a point spaced from said core and adjacent the other end of said gap so that the contact pressure is increased in response to excess currents in the circuit.

4. A circuit interrupter, comprising, separable contacts which are biased into engagement to automatically close the circuit following a circuit interrupting operation, a solenoid coil connected in series circuit relation with said contacts, means forming a low reluctance path for the flux of said coil outside of said coil and terminating adjacent the ends of said coil to form a working gap within said coil, a solenoid core biased to a normal position at one end of the working gap of said coil and from which it is moved by attraction of said coil on overload currents a predetermined distance before causing movement of one of said contacts away from the other to open the circuit, means of magnetic material secured to said one contact and being positioned adjacent the other end of said working gap and within the adjacent end of said low reluctance path means, so that the contact pressure is increased in response to excess currents in the circuit and is decreased when said core has traversed said predetermined distance.

5. A circuit interrupter, comprising, separable contacts which are biased into engagement, overload-responsive means including an operating part having lost motion with respect to one of said contacts and being biased to a normal position from which said part must be moved a predetermined amount before causing separation of said contacts, magnetic means responsive to overloads to exert additional pressure on said contacts, and magnetic shunting means movable with said operating part so that when the latter moves an amount less than said predetermined amount from its normal position said additional pressure

magnetic means is shunted and thus rendered substantially less effective.

6. A circuit interrupter, comprising, separable contacts which are biased into engagement, overload-responsive means including an operating part having lost motion with respect to one of said contacts and being biased to a normal position from which said part must be moved a predetermined amount before causing separation of said contacts, magnetic means responsive to overloads to exert additional pressure on said contacts, and magnetic shunting means movable with said operating part so that when the latter moves an amount less than said predetermined amount from its normal position said additional pressure magnetic means is shunted and thus rendered substantially less effective.

7. An automatic reclosing circuit breaker comprising, separable contacts which are biased into engagement, an operating rod directly connected with one of said contacts and movable in one direction to separate said contacts, a solenoid coil connected in series circuit relation with said contacts and positioned about said rod, a solenoid core slidably mounted on said rod, a coil compression spring mounted on said rod and reacting between said core and an abutment on said rod to bias the core to its normal position adjacent one end of said coil, and said abutment being of a magnetic material and located in the field of said coil at a point adjacent the other end of said coil so as to be acted upon by said coil in response to heavy overload currents to increase the pressure on said contacts.

8. An automatic reclosing circuit breaker, comprising, separable contacts which are biased into engagement, an operating rod directly connected with one of said contacts and movable in one direction to separate said contacts, a solenoid coil connected in series circuit relation with said contacts and positioned about said rod, a solenoid core slidably mounted on said rod, a coil compression spring mounted on said rod and reacting between said core and an abutment on said rod to bias the core to its normal position adjacent one end of said coil, means forming a low reluctance path outside of said coil terminating adjacent opposite ends of the coil, and said abutment being of a magnetic material and located adjacent the other end of said coil and in the adjacent end of said low reluctance path so as to be acted upon by said coil in response to overload currents to increase the pressure on said contacts, and to substantially decrease such additional pressure as said core is moved by the coil to actuate said rod to separate the contacts.

9. An automatic reclosing circuit breaker, comprising, separable contacts which are biased into engagement, an operating rod directly connected with one of said contacts and movable in one direction to separate said contacts, a solenoid coil connected in series circuit relation with said contacts and positioned about said rod, a solenoid core slidably mounted on said rod, a coil compression spring mounted on said rod and reacting between said core and a pin extending transversely through said rod to bias the core to its normal position adjacent one end of said coil, and said pin being of a magnetic material and located in the field of said coil at a point adjacent the other end of said coil so as to be acted upon by said coil in response to heavy overload currents to increase the pressure on said contacts.

10. An automatic reclosing circuit breaker, comprising separable contacts which are biased

into engagement, an operating rod directly connected with one of said contacts and movable in one direction to separate said contacts, a solenoid coil connected in series circuit relation with said contacts and positioned about said rod, a solenoid core slidably mounted on said rod, a coil compression spring mounted on said rod and reacting between said core and a collar on said rod to bias the core to its normal position adjacent one end of said coil, and said collar being of a magnetic material and located in the field of said coil at a point adjacent the other end of said coil so as to be acted upon by said coil in response to heavy overload currents to increase the pressure on said contacts.

11. A circuit interrupter, comprising, separable contacts, a solenoid coil connected in series circuit relation with said contacts, means forming a low reluctance path for the flux of said coil outside of said coil and terminating adjacent the ends of said coil to form a working gap within said coil, a solenoid core biased to a normal position at one end of the working gap of said coil and from which it is moved by attraction of said coil on overload currents a predetermined distance before causing movement of one of said contacts away from the other to open the circuit, means of magnetic material secured to said one contact and being positioned adjacent the other end of said working gap and the adjacent end of said low reluctance path means, so that the contact pressure is increased in response to excess currents in the circuit and is decreased when said core has traversed said predetermined distance.

12. A circuit interrupter, comprising, separable contacts, a solenoid coil connected in series circuit relation with said contacts, means forming a low reluctance path for the flux of said coil outside of said coil and terminating adjacent the ends of said coil to form a working gap within said coil, a solenoid core biased to a normal position at one end of the working gap of said coil and from which it is moved by attraction of said coil on overload currents a predetermined distance causing movement of one of said contacts away from the other to open the circuit, means of magnetic material secured to said one contact and being positioned adjacent the other end of said working gap and the adjacent end of said low reluctance path means, said means of magnetic material having a mass which is materially less than that of the means forming said low reluctance path, so that the contact pressure is increased in response to excess currents in the circuit and is decreased when said core has traversed said predetermined distance.

13. A circuit interrupter, comprising, separable contacts, a solenoid coil connected in series circuit relation with said contacts, means forming a low reluctance path for the flux of said coil outside of said coil and terminating adjacent the ends of said coil to form a working gap within said coil, a solenoid core biased to a normal position at one end of the working gap of said coil and from which it is moved by attraction of said coil on overload currents a predetermined distance before causing movement of one of said contacts away from the other to open the circuit, means of magnetic material secured to said one contact and being positioned adjacent the other end of said working gap but spaced from the adjacent end of said low reluctance path means, said means of magnetic material having a mass which is materially less than that of the

means forming said low reluctance path, so that the contact pressure is increased in response to excess currents in the circuit and is decreased when said core has traversed said predetermined distance.

14. A circuit interrupter, comprising, separable contacts, a solenoid coil connected in series circuit relation with said contacts, means forming a low reluctance path for the flux of said coil outside of said coil and terminating adjacent the ends of said coil to form a working gap within said coil, a solenoid core biased to a normal position at one end of the working gap of said coil and from which it is moved by attraction of said coil on overload currents a predetermined distance before causing movement of one of said contacts away from the other to open the circuit, means of magnetic material secured to said one contact and being positioned adjacent the other end of said working gap but spaced from the adjacent end of said low reluctance path means in a direction toward said one end of the gap, said means of magnetic material having a mass which is materially less than that of the means forming said low reluctance path so that the contact pressure is increased in response to excess cur-

rents in the circuit and is decreased when said core has traversed said predetermined distance.
ANDREW W. EDWARDS.
